METAL SEAMLESS TUBE TABLE

Samuel Victor, Chicago, Ill., now by judicial
change of name, Sam Women Sam

Application March 25, 1948, Serial No. 17,032

3 Claims. (Cl. 311—1)

1

My invention relates to tables especially of the kitchen-dinette type.

An object of my invention is to provide a table which can be made integrally in one piece of metal, substantially completely by a single cold extrusion and which is extremely thin-walled, light weight, highly corrosion resistant, resilient, adequately strong, durable, economical and whose top is rigid.

Other objects and advantages become apparent as the description proceeds.

I attain these objects by the structure illustrated in the accompanying drawing which is a perspective view of the table.

The table consists of a rectangular tube 1 whose opposite ends are open, which has an axis 6 (indicated by the double headed arrow), which has a horizontal top wall 13 of a length and width suitable for use as a table, two side walls 3 and 8 of a height suitable as the height for a table, and whose thin bottom wall 5 lies without interference flat on a floor on which the table may rest. The rectangular tube 1 also comprises a horizontal sheet 9 close to the horizontal top wall 13 and coextensive with said top wall 13. The side edges of horizontal sheet 9 are formed integrally with the side walls 3 and 8. The rectangular tube 1 also comprises a plurality of vertical sheets 11 and oblique sheets 10 which extend coaxially with the axis 6 of the rectangular tube 1 and which are interposed between the horizontal wall 13 and the horizontal sheet 9 and whose top and bottom edges are formed integrally with the horizontal top wall 13 and horizontal sheet 9 respectively and whose side edges are substantially coterminous with the horizontal top wall 13 and the horizontal sheet 9 along the opposite open ends of the rectangular tube 1. The top horizontal wall 13, the horizontal sheet 9, the plurality of coaxially extending vertical sheets 11 and oblique sheets 10 and the portion of the side walls 3 and 8 interposed between top horizontal wall 13 and horizontal sheet 9 altogether combine to form an integral assemblage of the total elements of a triangular truss construction coextensive with the top horizontal wall 13 substantially as illustrated in my perspective drawing, which makes for a rigid table top.

The rectangular tube 1 also comprises triangle-forming metal sheet braces 2, 4, 7 and 12 in its four corners, which braces extend from one open end of said rectangular tube 1 to the opposite end of latter tube 1.

The rectangular tube 1, horizontal sheet 9, 55

2

said plurality of vertical sheets 11 and oblique sheets 10 and said four triangle-forming braces 2, 4, 7 and 12 altogether being integral elements of the table formed in one piece of metal and being preferably extremely thin. This table is adapted to be made entirely by a single cold extrusion completely except for rounding and smoothing of all the edges at both open ends of the rectangular tube 1.

I claim:

1. A table comprising a substantially rectangular seamless integral tube whose opposite ends are open, the horizontal top wall of said tube being of a length and width suitable for use as a table top, the vertical side walls of said tube being of a height suitable as the height for a table, said tube having a horizontal seamless integral sheet substantially coextensive with said horizontal top wall of said tube, positioned below and close to said horizontal top wall, opposite edges of said horizontal sheet being formed integrally with said vertical side walls of said tube; said tube also comprising a plurality of sheets extending coaxially in relation to the axis of said rectangular tube interposed between said horizontal top wall and said horizontal sheet, extending from said horizontal top wall to said horizontal sheet, whose top and bottom edges are formed integrally with said horizontal top wall and said horizontal sheet respectively, and whose side edges are substantially coterminous with the side edges of said horizontal top wall and said horizontal sheet along said opposite open ends of said rectangular tube; said top horizontal wall, said horizontal sheet, said plurality of coaxially extending sheets and the portion of said side walls interposed between said horizontal top wall and said horizontal sheet altogether combining to form an integral assemblage of the total elements of a triangular truss construction substantially coextensive with said horizontal top wall substantially as described; said rectangular tube, said horizontal sheet and said plurality of coaxially extending sheets being integral elements of said table.

2. A table as set forth in claim 1, which comprises triangle-forming sheet braces in the four corners of said rectangular tube formed integrally with said tube substantially as described; said braces extending substantially from one open end of said tube to the opposite open end of said tube.

3. A table as set forth in claim 1, which comprises a pair of triangle-forming sheet braces in its two bottom corners substantially as de-

scribed; said braces extending from one open end of said tube to the opposite open end of said tube.

SAMUEL VICTOR,
Now by Judicial Change of Name Sam Women
Sam.
